UNITED STATES PATENT OFFICE

CLYDE ALSTON NELSON, OF CRISTOBAL, CANAL ZONE.

CONCRETE-BUCKET.

1,210,196.

Specification of Letters Patent. Patented Dec. 26, 1916.

Application filed September 21, 1916. Serial No. 121,454.

To all whom it may concern:

Be it known that I, CLYDE A. NELSON, a citizen of the United States, and a resident of Cristobal, Canal Zone, Panama, have invented a new and Improved Concrete-Bucket, of which the following is a full, clear, and exact description.

My invention relates to buckets employed in depositing concrete at great depths as for example in a cylinder and the like as used in forming dock foundations in deep water.

More particularly the invention relates to buckets having dumping bottoms and means to release the bottoms for depositing the concrete when a bucket reaches the lowered position. Usually two cables are employed for hoisting and lowering a bucket of the class referred to and controlling the dumping bottom.

General objects of my invention are to do away with the use of one of the cables usually employed, thereby obviating the twisting of the cables; and to provide means to insure the automatic dumping of the concrete when the bucket reaches the lowered position, so that the concrete will unfailingly be deposited.

More specific objects of the invention are to provide a simple and durable controlling means for the dumping bottom, of a character to withstand hard usage and so arranged that when the bucket is raised after dumping, the bottom may be readily closed and its controlling means quickly and conveniently adjusted to hold the bottom securely in the closed position while loading the bucket and until the loaded bucket again reaches the lowered position.

Other objects of the invention and the advantages of the novel structural details entering into the preferred embodiment of the invention will appear as the description proceeds.

Reference is to be had to the accompanying drawings forming a part of this specification in which similar reference characters indicate corresponding parts in all the views.

Figure 1 is a vertical section of a concrete bucket embodying my invention; Fig. 2 is a side elevation of the upper portion of the bucket, the view being taken at right angles to Fig. 1; Fig. 3 is a horizontal section on the line 3—3, Fig. 1; Fig. 4 is an inverted plan view of the bucket.

In carrying out my invention in accordance with the illustrated example, a bucket body 10 is made cylindrical as usual and is provided with a bottom 11 adapted to dump by gravity. The said bottom is disposed at one side of the bucket and at the opposite side, the interior of the bucket is formed with an incline 10^a which may be backed by a suitable block 10^b. The bucket is thus tapered at one side toward the dumping bottom 11. In the illustrated example, the bottom has bars 12 secured between angle irons 14, and said bars are pivotally secured by bolts 13 passing through angle irons 16 and provided with nuts 15.

The bail 17 is rigidly secured to the bucket and preferably is offset laterally at its upper end. To said bail is pivoted one end of a vertical swinging lever 18 having suitable means for attaching a cable 20 thereto, there being shown for the purpose a shackle 19 on said lever between the ends thereof. The arrangement is such that when the cable is relieved of the weight of the bucket, the lever 18 will drop by gravity from a normal horizontal position above the top of the bucket bottom.

A short length of cable 21 or equivalent flexible element is provided at its upper end with a loop or ring 22 adapted to hook over the lever 18 at the opposite end from the pivot thereof, and the lower end of said element 21 is connected with the dumping bottom 11 near the free end of the latter, the connection being effected in the present example by an eye bolt 23.

In use, the dumping bottom is closed and the ring 22 hooked over the lever 18. The bucket is now loaded with concrete and lowered by means of the cable 20 to the depth at which the concrete is to be dumped. When the bucket comes to rest and the cable 20 is thereby relieved of the weight of the bucket, the lever 18 will gravitate to the dotted line position indicated in Fig. 1, thereby disengaging the loop 22 of the element 21. Upon the bucket being now hoisted, the bottom 11 is free to drop as indicated in dotted lines, Fig. 1, thereby depositing the concrete.

To arrest the downward movement of the element 21, when the bottom 11 drops, a stop 25 which may consist of a hook bolt and nut secured to the element 21 will engage an eye bolt or equivalent guide member 24.

on the bucket through which the said element 21 is guided. Thus, the element 21 will be arrested in its downward movement and the downward movement of the bottom 5 21 thus limited. The co-acting elements 24, 25 therefore serve to maintain the upper end of the element 21 at such a height in the bucket 10 as to permit of the ring 22 being readily grasped by the workman when 10 the bucket is raised for again hooking said ring over the lever 18.

In order to limit the upward swing of the lever 18, and position the same horizontally for receiving the ring 22, suitable limiting 15 means are provided, said means preferably consisting of a short length of cable 26 secured at its ends to opposite sides of the bucket 10 by shackles 27 or the like, the said cable 26 passing through a transverse hole 20 28 in the lever 18 or otherwise suitably engaged with said lever.

Having thus described my invention I claim as new, and desire to secure by Letters Patent:

25 1. In a bucket of the class described, a bucket body, a bottom for said bucket connected therewith to dump by gravity, pivoted means on the bucket for connection with a lowering and hoisting cable, and 30 means connected with the dumping bottom and detachably engaging the first-mentioned means to subject said first means to the load imposed on the dumping bottom and exert a downward pull on said first means, 35 said second means being adapted to completely detach itself from the first means when said first means is relieved of the weight of the load by the bucket coming to rest in the lowered position.

40 2. A bucket of the class described having a dumping bottom, a lever fulcrumed on the bucket and provided with cable attaching means, and an element connected with said bottom and adapted to detachably engage 45 the said lever to hold the bottom in the closed position.

3. A bucket of the class described having a bucket bottom and a bail, a lever pivoted at one end on said bail and provided, between the ends of said lever, with means 50 for connection with a cable, said lever being adapted to drop when the cable is relieved of the weight of the bucket, and adapted to be swung upwardly by the cable when the latter is subjected to the weight of the bucket, an element connected with said dumping bottom, and means to detach-

ably engage said element with said lever at the end opposite the pivot.

4. A bucket of the class described having 60 a dumping bottom and a bail, a lever pivoted at one end on said bail, and provided, between the ends of the lever, with means for connection with a cable, said lever being adapted to drop when the cable is relieved 65 of the weight of the bucket, and to be swung upwardly by the cable when the latter is subjected to the weight of the bucket, an element connected with said dumping bottom, means to detachably engage said element with the lever at the opposite end from the pivot, and means independent of said element to limit the upward movement of the lever.

5. A bucket of the class described having 75 a dumping bottom and a bail, a lever pivoted at one end on said bail, and provided, between the ends of the lever, with means for connecting with a cable, said lever being adapted to drop when the cable is relieved 80 of the weight of the bucket, and to be swung upwardly by the cable when the latter is subjected to the weight of the bucket, an element connected with the dumping bottom and extending upwardly therefrom, 85 means on said element at the upper end to detachably engage the lever at the opposite end from the pivot, said element when released from the lever being adapted to be carried downward by the bottom when 90 dumping, and co-acting means on the bucket and on said element to arrest the downward movement of said element and limit the downward movement of the said bottom.

6. A bucket of the class described having 95 a dumping bottom and a bail, a lever pivoted at one end on said bail, and provided, between the ends of the lever, with means for connection with a cable, said lever being adapted to drop when the cable is relieved 100 of the weight of the bucket, and to be swung upwardly by the cable when the latter is subjected to the weight of the bucket, an element connected with said dumping bottom, means to detachably engage 105 said element with the lever at the end opposite the pivot, and a flexible element secured at its opposite ends to the bucket, said flexible element having connection with said lever to limit the upward swing of the 110 latter to position said lever for engagement with the first element.

CLYDE ALSTON NELSON.
